POULTRY SHACKLE

Paul J. Altenpohl, Philadelphia, Pa.

Application September 11, 1950, Serial No. 184,295

3 Claims. (Cl. 17—44.1)

1

This invention relates to new and useful improvements in poultry shackles.

The primary object of this invention is to provide a poultry shackle which will automatically clasp the leg of the fowl upon the same being placed between the gripping elements thereof.

Another important object of this invention is to provide a device of this character in which the gripping elements thereof will be automatically and releasably retained in the open position upon being moved to such position.

Still another object of this invention is to provide a device of this character which will include a pair of leg gripping units that may be independently actuated to grip a leg of the fowl.

Yet another important object of this invention is to provide a device of this character in which each of the gripping units may be simultaneously actuated for the release of the legs of the fowl from between the gripping elements thereof, and, in conformity with the preceding objects, a device wherein, when the gripping units are actuated for the release of the fowl, the gripping elements will be automatically retained in such releasing position.

A meritorious feature of the present invention resides in the means for actuating opening and closing movement of the gripping jaws, and the provision of such means for each of the shackle units, whereby the shackle units may be independently actuated.

Still another important feature of the present invention resides in the combined trigger and latching means for holding the gripping jaws in the open position.

A final important feature to be specifically enumerated herein resides in the moving parts of the shackle unit with the exception of the necessarily exposed portions of the jaws and the trigger being enclosed to serve the interests of sanitation and longer life for the moving parts, together with the common means for actuating opening movement of both of the pairs of jaws.

These, together with various ancillary objects and features of the invention which will become apparent as the following description proceeds, are attained by the present invention, a preferred embodiment of which has been illustrated by way of example only in the accompanying drawings, wherein:

Figure 1 is a side elevational view of the present invention, the outlines of certain concealed portions of the same being indicated in dotted outline, and showing the same with the jaws in the closed position;

2

Figure 2 is an end elevational view of the device as shown in Figure 1;

Figure 3 is a horizontal sectional detail view of one of the shackle units, this view being taken substantially upon the plane of the section line 3—3 of Figure 1;

Figure 4 is a central vertical sectional view of the present invention with the jaws in the open position, this view being taken upon the plane of the section line 4—4 of Figure 5;

Figure 5 is a horizontal sectional view of the device as shown in Figure 4, this view being taken upon the plane of the section line 5—5 of Figure 4;

Figure 6 is a vertical transverse sectional view taken upon the plane of the section line 6—6 of Figure 4;

Figure 7 is a perspective view of the combined trigger and latch member; and

Figure 8 is a perspective view of one of the jaws utilized in the device.

Reference is now made more specifically to the accompanying drawings, wherein like numerals designate similar parts throughout the various views, and in which the poultry shackle is designated generally at 10.

The shackle 10 comprises a frame 11 formed of oppositely extending shackle units 12 and 14 connected at their adjacent ends by a substantially U-shaped body 16.

Inasmuch as the shackle units 12 and 14 are identical, it is believed that a description of one will suffice for both. The shackle unit 14 consists of a housing formed by a plate 18 integral with the body 16 and projects laterally therefrom, the plate 18 carrying spaced side walls 20, with a bottom closure plate 22 being provided that is secured to the walls 20 by fasteners 24 and to the plate 18 by spaced fasteners 26 that extend across the space between the plate 22 and the plate 18 for a purpose to presently appear.

A pair of jaws 28 and 30 are disposed between the plates 18 and 22 and project outwardly in between the plates 18 and 22 to terminate in offset hooked portions 32 and 34, respectively, said jaws 28 and 30 being pivoted upon the fasteners 26 for relative opening and closing movement of the offset portions 32 and 34. It will be noted that the portions 32 and 34 of the jaws are offset so that when the jaws are swung into the closed position such portions are in overlapping relationship as shown in Figures 1 and 3.

Means is provided for opening and closing the jaws and for also resiliently urging the jaws 55 towards the closed position. As best shown in

Figure 5, the jaws 28 and 30 include offset overlapping portions 36 and 38, such overlapping portions 36 and 38 being received between the upper and lower legs 39 and 40, respectively, of a U-shaped member slidably mounted between the plates 18 and 22, the portions being pivotally mounted on a pivot pin 42 extending between the legs 39 and 40, the arrangement being such that upon movement of the pivot pin 42 toward the projecting ends of the jaws, such jaws will be urged to an open position, and upon movement of the pin 42 in the opposite direction, the jaws will be urged into closed position, it being understood that the pivotal connection between the pivot pin 42 and the portions 36 and 38 will be sufficiently loose due to the provision of the slots 41 and 43 in the portions 36 and 38, respectively, receiving the pivot pin 42 so as to afford the requisite degree of lost motion between the swinging movement of the jaws 28 and 30 and the reciprocating movement of the pin 42 between the pivotal fasteners 26.

The legs 39 and 40 are connected by a web 44 having adjustable threaded engagement with one end of a plunger rod 46 that has an enlargement 48 on its other end that is slidable between the plates 18 and 22 and the side walls 20. An intermediate portion of the rod 46 is slidable through an apertured guide plate 50 extending between the plates 18 and 22 and which is located in recesses 52 in the side walls 20 to prevent movement thereof as clearly shown in Figures 3 and 4. A coiled compression spring 54 is disposed about the rod 46 and seated between the plate 50 and the enlargement 48 to urge movement of the rod 46 from the jaws 32 and 34, thus moving the pivot pin 42 to urge closing movement of the jaws.

As thus far described, it will be readily apparent that movement of the rod 46 toward the jaws will open the latter, whereas movement of the rod 46 under the action of the spring 54 will cause the jaws to close.

Means is provided for releasably latching the jaws in the open position, which means will be responsive to an object being pressed inwardly between the jaws to unlatch the latter. Such means comprise a generally U-shaped combined trigger and latch member designated generally at 56 and shown in perspective in Figure 7. The member 56 includes spaced legs 58 connected by a web portion 60, such legs 58 having elongated slots 62 therein. As best shown in Figure 4, the member 56 is slidably disposed between the jaws 28 and 30 and the closure plate 22, with the web portion 60 projecting outwardly from between the plates 18 and 22 closely adjacent the space between the jaws 28 and 30 when the latter are in the open position shown in Figure 5, and with the legs 58 disposed on opposite sides of the lower leg 40 and with the pivot fasteners 26 slidably received through the slot 62. It will thus be seen that the member 56 is free to reciprocate to an extent limited by the length of the slot 62 and that the same may be moved by an object placed between the jaws and pressed against the web portion 60. The free ends of the legs 58 are provided with laterally projecting lugs 64 that engage with locking dogs 66 formed on the jaws 28 and 30 when the latter are in the open position shown in Figure 5. However, the lugs 64 may be disengaged from the locking dogs 66 upon sliding movement of the member 56 away from the portions 32 and 34 of the jaws. The member 56

is biased toward the portions 32 and 34 so that the lugs 64 will engage the locking dogs 66 whenever the jaws are opened by means of plungers 68 slidably mounted in recesses 70 provided in the side walls 20. The plungers 68 engage the lugs 64 and are urged toward the latter by compression springs 72 disposed in the recesses 70 and bearing against the inner end of the plungers 68.

Means is provided for opening the jaws of the shackle units 12 and 14 which include hand levers 74 carried by the body 16. As best shown in Figure 4, the levers 74 extend through suitable openings 76 in the body 16 and have their lower ends 78 received in apertures 80 formed in the enlargement 48. The levers 74 are pivoted intermediate their ends by pins 82 in the openings 76 so that the oscillation of the levers 74 about their pivots will be accompanied by reciprocation of the rod 46, and vice versa. It will be noted, upon comparing Figures 1 and 4, that when the jaws are closed and the enlargements 48 in their closest proximity that the upper portions of the levers 74 are swung outwardly from the body 16 so that the upper portions may be gripped in the hand and urged together to force the jaws open against the action of the springs 54, it being noted that when the jaws are in the open position, as in Figure 4, that the upper portions of the levers 74 are received within recesses 84 at the top of the body 16 and that the lower portion of the levers 74 are received within recesses 86 at the bottom of the body 16, it being noted that the levers 74 are offset adjacent their pivotal connections so as to snugly fit into said recesses 84 and 86.

In order that the poultry shackle 10 may be conveniently suspended from an overhead support or secured to a conveyor chain or the like, the upper end of the body 16 is provided with a U-shaped securing loop 88 that is secured to the body 16 by means of a suitable fastener 90.

It will now be evident that there has been provided a poultry shackle which includes two shackle units that may be individually actuated to hold the leg of a fowl, and that such poultry shackle will suspend the poultry in a vertical position most convenient for the cleaning and dressing of the latter. It should be pointed out in passing that suspending poultry in the vertical position permits the proper drainage of blood therefrom after the killing operation, and that while so held securely by the present invention, the hocks thereof may be thoroughly cleaned, a difficult operation when using extant poultry shackles.

Since, from the foregoing, the construction and advantages of this poultry shackle are readily apparent, further description is believed to be unnecessary.

However, since numerous modifications and equivalents will readily occur to those skilled in the art after a consideration of the foregoing specification and accompanying drawings, it is not intended to limit the invention to the exact embodiment shown and described, but all suitable modifications and equivalents may be resorted to which fall within the scope of the appended claims.

Having described the invention, what is claimed as new is:

1. A poultry shackle comprising a generally T-shaped body, a pair of oppositely directed shackle units carried by said body, each of said shackle units comprising a pair of cooperating

jaws, said jaws being disposed between a pair of plates forming a portion of said body and pivotally connected together by a first pivot pin and to said plates by second pivot pins for relative opening and closing swinging movement, an operating rod slidably mounted in said body for movement for selectively urging said jaws into open and closed positions, said rod being connected to said first pivot pin, spring means carried by said body urging said rod to a jaw closing position, locking dogs on said jaws, a combined latch and trigger member slidably mounted between said plates for movement between a first position engaging the locking dogs to prevent closing movement of the jaws and a second position disengaging said jaws, said member being spring-urged toward said first position, said member projecting from between the plates adjacent the jaws to be moved by an object disposed between the jaws toward the second position.

2. The poultry shackle of claim 1 wherein the

rods of said shackle units are in alignment and have spaced opposed inner ends, levers pivotally carried by said body having ends engaged with said rods for movement therewith, whereby said levers may urge said rods to jaw-opening positions.

3. The poultry shackle of claim 1 wherein said combined latch and trigger member is retained between said plates by said second pivot pins.

PAUL J. ALTENPOHL.
